Specification of Letters Patent. Patented Jan. 26, 1915.

Application filed November 18, 1907. Serial No. 402,033.

To all whom it may concern:

Be it known that I, JOSEPH L. WRIGHT, a citizen of the United States, residing at Cleveland, in the county of Cuyahoga and 5 State of Ohio, have invented certain new and useful Improvements in Telephone-Exchange Systems, of which the following is a specification, reference being had therein to the accompanying drawing.

10 My invention relates to telephone exchange systems and particularly to semi-automatic systems in which a portion or all of the work of interconnecting subscribers is done by machines controlled by operators.

15 The object of the invention is to provide a convenient, economical and efficient circuit of the sending or signal transmitting apparatus, and also to simplify the mechanical parts of the signal apparatus.

The characteristic features of my invention are these: A series of sets of teeth, each set having teeth from 1 to 10, are arranged upon a common shaft and springs adapted 20 to be operated by the teeth are connected to corresponding push buttons before the operator. When any number desired has been set up by depressing the corresponding button, a set of associated relays are pulled up 25 and locked on a battery circuit which includes a series of contacts controlled by teeth on disks or break wheels rotated synchronously with the number wheels and acting to cut off the battery from the locking 30 wires successively once in each complete rotation. One of these relays is a guard for the other, so that they must be unlocked in inverse order, that is, the last one first, in order to produce any effect. The impulse 35 wires from the push buttons pass through back contacts on the last relay and front contacts on the first relay in series with the contacts on the intermediate relays and finally to the trunk or other wires leading to 40 automatic switches which are the subjects of control. Thus, when the last relay is unlocked and lets go, this circuit is complete, and as this occurs at the beginning of a revolution, when the signal which has 45 been sent, immediately starts through its proper strip of keys. At the end of one revolution the next to the last relay is cut off and so on at every revolution, one relay 50

being cut off and properly transferring the circuit to its proper strip of keys until the first relay lets go, disconnecting the signaling apparatus from the trunk wires.

I have illustrated my invention in the accompanying drawings as applied to a common battery system, in which the operator plugs into the trunk jack and sets up the switches by means of the impulses from the sending machine. The push buttons used are preferably provided with latches and are interlocking so that the depression 65 of any one push button in a strip releases any other that may have been previously depressed in that strip.

Figure 1 in the accompanying drawings is a diagram of a subscriber's line, of a trunk terminal and an operator's cord circuit for interconnecting them. Fig. 2 is a diagram embodying the circuits of my invention and includes the operator's sending apparatus. Fig. 3 is a diagram of a first selector, second selector and connector switch of the ordinary Strowger type. Figs. 4 and 5 are respectively front and end views of the sending machine. Fig. 6 is an end view of a modified form of the sending machine.

Referring to Fig. 1, A is a subscriber's station, equipped with apparatus usual in common battery systems, consisting of the transmitter, receiver, switch hook, ringer and condenser. From this sub-station the line wires 1 and 2 extend to the central office, where they pass through the normally closed contacts of the cut off relay M' to the line relay M and ground respectively. The relay M is connected on the other side 65 to main battery B and controls a signal lamp L, associated with the answering jack J.

The answering jacks J are supposed to be grouped in a convenient manner together 95 with their signal lamps L in front of the operators and when any line is calling it is intended that it shall be connected through a trunk jack J' with trunk lines leading to a first selector switch.

In order to interconnect the line to trunk jacks, I provide a pair of plugs P and P', having their tips and sleeves respectively connected through the conductors 3-5 and 4-6, these conductors being separated by 105 the condensers C and C'. The answering

plug P has associated with it a supervisory lamp L', controlled by the relays R and R'. The relay R' is placed in series with the cut off relay M', when the plug is placed in the 5 jack J and the relay R has its circuit closed through the subscriber's telephone.

The calling plug P' has three conductors which I shall call the tip p, ring p' and sleeve p'', the ring in this case corresponding to the 10 sleeve of the plug P. When the plug is inserted in the trunk jack J', the tip and ring are connected respectively with the jack springs j and j', while the sleeve p'' comes into contact with the thimble j'' connected 15 through a resistance coil j''' to ground. This thimble connection is for testing, and also furnishes or completes the circuit of the cut-off relay R' when the plug is inserted. The two relays R' and R'' are associated together 20 for controlling the connection of the operator's telephone. The relay R' gets current through the wires 17 and 18 when the plug P is first inserted in the answering jack, the circuit B, 19, 17 and 18 and ground being 25 then immediately closed by the relay R' pulling up. The relay R', therefore, pulls up, while the relay R'' which controls it remains deenergized, and relay R' in pulling up closes the two sides of the operator's secondary circuit with the receiver in series therewith onto the wires 7 and 8, and from there across the cord conductors 3 and 4, enabling her to converse with the calling subscriber.

The primary i' is included in a shunt circuit 13-14, with the condenser C' and the transmitter T, the latter deriving its current supply direct from main battery through the choke-coil j'' by the circuit B, 20, 21, 22 and ground. The third winding i'' is included in 35 the test circuit 11 and 28, which passes from ground through to back contact on the relay R' to the tip conductor 5 and so on to the tip of the calling plug P'. Each cord circuit is equipped with a switching key O, 40 which corresponds to the ordinary ringing key in manual practice. Instead of the wires from this key leading to a ringing generator, they lead directly to a pair of contacts on one of the relays controlling the 45 impulses from the sending machine. Each operator of course is provided with a certain percentage of these cord circuits, enabling her to handle all incoming calls and to complete the connections for the same, and it of course follows that each operator will be 50 provided with a set of these control relays, which can be made common to her set of cords and plugs by means of the switching key O, with which each cord circuit is 55 equipped. The sending machine itself can of course be common to the entire exchange, or it can be duplicated, it being only necessary to state that a set of keys and controlling relays are individual to each operator 60 and common to her connective apparatus.

The trunk wires 105 and 106, which terminate in jacks J', can be multiplied to all of the sections of the switch-board, or any operator can have an individual set before her. Where they are multiplied an operator tests 70 by applying the tip p of her plug P' to the thimbles j'' of successive jacks until the absence of a click indicates one which is idle.

Referring now to Fig. 3, I have shown circuits of a first selector, second selector and connector switches, as described in Letters Patent 815,321 and 815,176, granted March 13, 1906, to Keith and Erickson. I will not describe these circuits in detail. The first selector switch X consists of the vertical relay D, which when energized closes the circuit of the vertical magnet V¹⁰, which in turn causes the spindle x, carrying the wipers to step up vertically. The rotary relay D', when energized operates the private relay F, 80 causing the side switches to make one step. The rotary magnet L¹⁰ has its circuit closed after the side switches have made one movement and will continue to vibrate, causing the spindle x to rotate until the test wiper 85 finds a contact free from ground. As soon as this happens, the side switches make still another movement, disconnecting the vertical and rotary relays from the trunk wires and closing the trunk wires themselves 90 through to the trunk wipers. The last movement of the side switches also connects the trunk release relay G to the test wiper. The magnet K is the release magnet and when operated restores the switch to its normal 95 position. The circuits of the second selector switch X' are similar to those of the first selector switch and need not be described.

Referring now to the connector switch x² the circuits shown are the same as in the 105 Letters Patent before referred to with the exception of placing the relay G² in place of the release magnet K². In this case, the release relay G² is first operated as though it were the release magnet and in turn closes 110 the circuit of the magnet K². Instead of testing on a third wire or test wiper, I do the testing directly on one side of the line or trunk. In place of the ordinary back release relays which were connected to the 115 trunk wires 163 and 164, respectively, I have replaced with the release relays D⁶ and D⁷ with bridged battery between them for supplying current to the called subscriber and also for controlling the ringing relay Y. 120 The ringing relay Y is energized when the sleeve relay D⁷ is energized and disconnected when the tip relay D⁶ is operated, closing the circuit of the relay D⁸ which locks and prevents generator current flowing out on 125 the line in case the called party should hang up his telephone first. This relay is kept locked by means of the contact springs x⁵ and x⁶ until the switch has been restored to its normal position. The vertical relay D⁴, 130

the rotary relay D^6 and the private relay F^2 remain unchanged and the method of operating and releasing the switch is the same.

Referring now to Figs. 2, 4 and 5, I will describe the sending machine and its circuits. The drum or cylinder A^{20} is made up of 16 disks or punchings. The first 10 of these disks from A to A^9 inclusive are used for transmitting impulses to operate the various automatic switches. The disk A is provided with one tooth, the disk A' with two teeth and so on up to disk A^9 which is provided with 10 teeth. The next 5 disks A^{10} , A^{11} , A^{12} , A^{13} , and A^{14} are each provided with one tooth for controlling the set of relays shown in Fig. 2. By referring particularly to Fig. 2 it will be seen that the teeth are arranged synchronously on the periphery of the drum. By noting the direction the wheels travel, as indicated by the arrow, it will be seen that the tooth on the wheel A^{10} travels in advance of the teeth on the other wheels, and that the tooth on the wheel A^{11} is in advance of the teeth on the remaining wheels. The tooth on the wheel A^{12} is in advance of the two remaining wheels, while the tooth on the wheel A^{14} is the last. The wheel A^{13} controls the relay S^4 while the wheel A^{14} controls the relay S .

Referring to the mechanical figures in Figs. 4 and 5, the remaining wheel or disk A^{15} is provided with one tooth which is used for sending the rotary or switching impulse to the automatic switches. All of these disks, which can be made of any suitable material, preferably of brass are bolted or clamped together by means of the bolts and nuts W^4 . These disks are all fixed fast to the shaft W' by means of a key or otherwise, which turns freely in the bushings W^2 . These bushings are fixed firmly in the brackets or braces W so as to form suitable bearing for the shaft. The braces themselves are fastened firmly to a base J by means of suitable bolts. A mounting plate W^3 is fastened to these brackets and carries the springs which are operated by the teeth on the various disks. These springs are mounted like relay springs, each set of springs being separated by the insulating blocks W^7 and clamped to the strip W^8 by means of the screws W^6 . Each set of springs, with the exception of the five which control the relays are normally open, while the latter are normally closed. These springs are operated by the teeth working the plungers W^5 , while the drum is rotating.

Referring now to Fig. 2, it will be seen that one spring of the set a , is connected directly to the first button in each strip of keys, one spring of the set a' to the second button in each strip and so on up until the ten sets are connected to the ten buttons. When the first button of any set or strip is closed, one impulse at each rotation will be

sent through to the common wire of each strip, and if the second button of each strip is down, that two impulses will be sent to the common wire of each strip. It, of course, follows that any button depressed will transmit the number of impulses corresponding to the number of teeth on the wheel to which it is connected. The series of relays shown are for transmitting these impulses in groups and in regular order so as to operate the automatic switches properly. The button e^{10} is for starting the impulses after the proper buttons have been set up. This button, when depressed, closes the circuit of the relay S , which then closes the circuit of the relay S' . The relay S' closes the circuit of the relay S^2 which closes the circuit of the relay S^3 and this relay in turn closes the circuit of the relay S^4 . While these relays are all energized, the trunk wires 15 and 16 are closed on to the extensions through the contact of the other relays, but as all of these relays are energized, the common wires 120, 119, 118 and 117 leading to the strips of buttons are disconnected, so of course no impulses can be transmitted. These relays, after the button e^{10} has been depressed, remain locked through the normally closed contacts a^{10} , a^{11} , a^{12} , a^{13} and a^{14} . The relay S is only locked through the contacts a^{14} , but the other relays, besides being locked through the contacts already mentioned are each locked through the contacts of the preceding relay, as plainly shown on the drawing. In other words, the relay S is the only one left unguarded. As soon as the tooth on the wheel A^{14} reaches the contact a^{14} , the relay S becomes deenergized and falling back, connects the common wire 117 to the wire 15 in series with the contacts of the relays S' , S^2 , S^3 and S^4 . As soon as the relay S falls back, impulses will be transmitted from the wire 117 through whichever button is down in the strip E . If #10 button is down, ten impulses will be transmitted to the wire 117 by means of the number wheel A^9 which is provided with 10 teeth. After one complete rotation, the relay S' falls back as the contacts a^{13} are broken by the tooth on the wheel A^{13} . This relay is enabled to fall back now because the relay S is deenergized and it is not guarded. The relay S' in falling back, opens the contacts s^{10} and s^9 , disconnecting the wire 117 from the trunk wire 15, and in its place connects the common wire 118 belonging to the strip of buttons E' . Impulses will now be sent over the common wire 118 through whichever button is down in the strip E' .

The strip of buttons E transmits impulses corresponding to the thousands and operates the first selector switch. The strip of buttons E' transmits the hundreds and operates the second selector switch, while the strips E^2 and E^3 transmit the tens and

units and operate the connector switch. After the second rotation, the relay S^2 falls back by the breaking of the contacts a^{12} by the tooth on the wheel A^{12} and disconnects the wire 118, and in its place connects the common wire 119 leading to the strip E^2 . At the end of the third rotation, or beginning of the fourth, the relay S^3 falls back by the breaking of the contacts a^{11} by the tooth 10 on the wheel A^{11} . This relay falling back, disconnects the wire 119 and in its place connects the common wire 120 leading to the strip of keys E^3 . After the fourth rotation, or at the beginning of the fifth, the relay S^4 falls back by the breaking of the contacts a^{10} by the tooth of the wheel A^{10} . (See Fig. 6.) This relay in falling back disconnects the trunk wires 15 and 16 from the last strip of keys, thereby preventing further impulses. At every rotation and immediately after each group of impulses a single impulse is sent to trunk wire 16 by the closing of the contacts a^{15} . This impulse is for operating or transferring the 25 side switches in the various selector and connector switches. The lamp L^2 has its circuit completed when the relay S^4 is energized and remains lighted until a complete set of impulses have been sent, or until the 30 drum makes four complete revolutions. This lamp remains lighted for the purpose of notifying the operator that the key set is busy and cannot be used until the lamp is extinguished.

35 In the drawing I have shown the springs a , a' etc. in pairs, operated by the respective teeth on the drum, but I may obviously use single springs bearing directly on the metal of the teeth, while the drum or frame 40 can be connected directly to ground. This arrangement is shown in end elevation in Fig. 6, but I consider the arrangement of Figs. 4 and 5 preferable.

By referring to Figs. 1 and 2, it will be 45 noticed that the operator's connective apparatus is connected to the sending device by means of the switching key O . When the operator desires to complete a connection, she throws this key forward, depresses the 50 proper buttons in the key set and then pushes the starting button and the impulses will then come from the trunk wires 15 and 16 to the connective apparatus and from there to the automatic switches in regular 55 order. As soon as the lamp L^2 is extinguished, after the impulses have been sent, the operator throws the switching key back to its normal position. It is necessary to throw the key in this manner as I have already 60 stated the keys and the relays are common to the connective apparatus and if the key O were left thrown over, impulses would of course go over the trunk again when she is putting through a call on some 65 other trunk. Of course if each cord circuit

were provided with a set of controlling relays, it would be unnecessary to provide the switching key O .

The operation of my system is as follows: The subscriber at station A, desiring to 70 make a call, removes his receiver, which closes the circuit of the relay M through the normally closed contacts of the relay M' , the relay M operating closes the circuit of the signal lamp L . The operator, upon getting 75 this signal, inserts the plug P into the jack J , thereby placing the relays M' and R' in series. The relay M' , in operating, disconnects the relay M , which upon falling back, extinguishes the lamp L , at the same 80 time the relay M' connects the trunk wires 1 and 2 to the extension leading directly to the springs of the jack J . The energizing of the relay R' closes the circuit of the relay R^3 from battery by wire 19 through the contacts of R' , through wire 17 to R^3 , through wire 18 and contacts of R^4 to ground. The relay R^3 in operating connects the operator's 85 secondary, which includes the receiver, directly across the tip and sleeve wires of the 90 answering plug P , thus enabling her to converse with the calling party. Upon getting the number desired, she picks up the plug P' and tests for an idle trunk jack by means of touching the tip of the plug P' to the 95 thimble of the jacks J' . When testing and touching the thimbles of busy jacks, she will receive a click through her receiver by induction through the third winding on the 100 induction coil. Having found an idle trunk jack, she inserts the plug P' into the jack connected to that trunk. The insertion of the plug closes the circuit of the relay R^4 in 105 series with the resistance coil attached to the thimble of the jack. The energizing of the relay R^4 opens the circuit of the relay R^3 , thereby disconnecting the operator's telephone set from the tip and sleeve of the 110 answering plug. The energizing of the relay R^4 disconnects the third or test winding 115 of the induction coil from the tip of the calling plug P' . Suppose the number desired by the calling party was 1234; the operator at once depresses or sets up the following buttons 120 on the key set: In the strip E she sets the first button e ; in the strip E' the second button e' ; in the strip E^2 the third button e^2 ; in the strip E^3 , the fourth button e^3 . Having set up the buttons corresponding 125 to the number desired, she throws forward the switching key O and then depresses the starting button e^{10} . In pressing the starting button, she closes the circuits of the control relays in the manner previously described. The relay S is now kept locked through the contacts a^{14} , the relay S' is kept locked through the contacts a^{13} and through the contacts s^3 and s^7 of the relay S , the relay S^2 is kept locked through the contacts 130

a^{12} and the contacts s^{13} and s^{14} of the relay S' ; the relay S^3 is kept locked through the contacts a^{12} and through the contacts s^{20} and s^{21} of the relay S^2 , while the relay S^4 is kept locked through the contacts a^{19} and the contacts s^{27} and s^{28} of the relay S^2 . The circuit of the lamp L^2 is completed through the contacts s^{36} and s^{37} of the relay S^4 . As soon as the relay S falls back when the tooth on the wheel A^{14} opens the contacts a^{14} the circuit is closed from the common wire 117 to the tip of the trunk and one impulse is sent thereon by the following path: ground, 115, a , 181, e , 117, s , s' , s^{10} , s^9 , s^{17} , s^{16} , s^{24} , s^{23} , s^{30} , s^{26} , 15, 0, 5, p , j to 105 side of the trunk leading to the first selector switch. This impulse closes the circuit of the relay D in the first selector switch X , causing the spindle carrying the wipers to step up to the first row of contacts. After this impulse, a single impulse is sent to the opposite side of the trunk by the following path: ground, A^{15} , 182, s^2 , s^3 , 121, s^{32} , s^{31} , 16, 0, 6, p' , j' to 106 side of the trunk. This impulse closes the circuit of the relay D' in the first selector switch, which in turn closes the circuit of the private relay F , causing the side switches to take one step cutting on the rotary magnet L^{10} . This rotary magnet as well as the succeeding rotary magnet L^{20} , has a circuit breaker or vibrator mechanism associated with its armature as indicated in the diagram by a pair of closed contacts between the coils, and an insulating wedge on the armature, adapted to separate them when it is pulled up on each vibration. Each magnet therefore constitutes in itself an automatic vibrator or "buzzer." The operation of the rotary magnet L^{10} causes the switch to rotate and continue until the test wiper finds an idle contact leading to a second selector switch. As soon as this happens, the relay F falls back, causing the side switches to take another step, thereby disconnecting the rotary magnet L^{10} . This last step connects the trunk wires directly to the trunk wipers leading to an idle second selector switch and also connects the trunk release relay G directly from ground to the test wiper, rendering the switch busy for other calls.

Referring again to Fig. 2, after the first vertical and rotary impulses have been sent the drum starts its second rotation, breaking the contacts a^{13} , disconnecting the relay S' . This relay in falling back disconnects the common wire 117 of the strip E from the wire 15 and in its place connects the common wire 118 of the strip E' through the contacts s^8 and s^9 . Two impulses are now sent over the tip or vertical side of the trunk through the button e' by means of the number wheel A' . These two impulses now close the circuit of the relay D^2 in the second selector switch X' , causing the switch spindle

carrying the wipers to step up vertically to the second row. After this group of impulses, a single rotary impulse is sent as before and operates the relay D^3 , which in turn closes the circuit of the relay F' , causing the side switches to take one step cutting on the rotary magnet L^{20} . Under the influence of this magnet the spindle rotates until the test wiper finds an idle contact whereupon the relay F' becomes deenergized and causes the side switches to take another step. This last step of the side switches disconnects the rotary magnet L^{20} and connects the trunk release relay G' directly from ground to the test wiper and also closes the trunk wires to the trunk wipers leading to an idle connector switch.

After the second group or set of impulses have been sent, the drum starts its third rotation, thereby opening the circuit of the relay S^2 at the contacts a^{12} . This relay falling back disconnects the common wire 118 of the strip E' from the wire 15 and in its place connects the common wire 119 of the strip E^2 . Three impulses are now sent over the vertical side of the trunk through the button e^2 by means of the number wheel A^2 . These impulses close the circuit of the relay D^4 , which in turn closes the circuit of the vertical magnet V^{30} , causing the spindle carrying the wipers to step up to the third row of contacts. After this set of impulses, a rotary impulse is sent over the opposite side of the trunk through the contacts a^{15} as before operating the relay D^5 , which in turn closes the circuit of the relay F^2 , causing the side switches to take one step, disconnecting the vertical magnet V^{30} and in its place connecting the rotary magnet L^{30} . This movement of the side switches also connects the test relay G^2 to the tip of the trunk through the normally open contacts of the relay F^2 . After this third group of impulses, and at the beginning of the fourth rotation, the relay S^2 has its circuit open at a^{11} and in falling back disconnects the common wire 119 of the strip E^2 and in its place connects the common wire 120 of the strip E^3 . Four impulses are now sent over the vertical side of the trunk through the button e^3 by means of the number wheel A^3 . These impulses operate the relay D^4 , which in turn closes the circuit of the rotary magnet L^{30} , which causes the switch to operate and bring the wipers to rest on contacts leading to the desired line, which in this case, is the fourth set. After this set of impulses a single rotary impulse is sent over the opposite side of the trunk, closing the circuit of the relay D^5 , which in turn closes the circuit of the relay F^2 , thereby connecting the test relay G^2 to the tip side of the trunk or line. If the line is busy, the relay G^2 becomes energized and closes the circuit of the magnet K^2 which restores the switch to its normal position.

tion. If the line is not busy, as we will suppose to be the case, the relay G^2 fails to get current and the side switches take another step, disconnecting the rotary magnet and test relay and connects the trunk wires through to the trunk wipers leading to terminals of the desired line. As soon as this condition is brought about, the relay D^7 is placed in series with the line cut off relay as in Fig. 1. The relay D^7 thereupon closes the circuit of the ringing relay Y by the following path: battery B , d^3 , d^2 , d^5 , d^4 , Y ; commutator to ground. By means of this commutator, generator current is sent out intermittently over the called line, thereby ringing the subscriber's bell. When the called subscriber answers, the relay D^6 becomes energized, when the ringing relay Y is deenergized. The operating of this relay 20 closes the circuit of the relay D^8 , which remains locked through the contacts x^5 and x^6 . The locking of this relay disconnects the ringing relay Y and prevents its operating in case the called party should hang up his 25 telephone first.

Referring again to Fig. 2, after the fourth set or group of impulses have been sent, the drum starting on its fifth rotation, opens the circuit of the relay S^4 through the contacts a^{10} . This relay, in dropping back, disconnects the wires 15 and 16 from the common wires 120 and 132 respectively, thus preventing further impulses being sent. The relay S^4 in falling back, also extinguishes 30 the lamp L^2 , notifying the operator that the call has been completed. Upon getting this signal, she restores the switching key O , thereby severing the wires 15 and 16 from the wires 5 and 6. At the end of the conversation, the calling party hanging up, opens 40 the circuit of the relay R , Fig. 1, which upon falling back, closes the circuit of the supervisory lamp L' , notifying the operator that the parties have finished talking. This relay R , in falling back, also connects ground to both sides of the trunk through the contacts r^{10} and r^9 of the relay R' . Ground being thus placed on both sides of the trunk at the same time closes the circuits 50 of the relays D^4 and D^5 in the connector switch, effecting its release and also releasing the first and second selector switches in the following manner: The operating of the relays D^4 and D^5 simultaneously places the relays G^2 and G' in series. The operating of the relay G^2 closes the circuit of the magnet K^2 , thereby restoring the connector switch X^2 to its normal position. The operating of the relay G' in the second selector 60 switch, places the magnet K' in series with the relay G in the first selector switch. The operating of the magnet K' restores the second selector switch X' , while the relay G closes the circuit of the magnet K , thereby 65 restoring the first selector switch X . When

the connector switch is restored the contacts x^5 and x^6 are broken, unlocking the relay D^8 .

Referring to Fig. 1, the operator getting the disconnect signal, withdraws the plug P from the answering jack J and the calling plug P' from the trunk jack J' , thereby restoring all parts to their normal condition.

It is to be understood that the description herein is made specific for purposes of definition and not of limitation, and I contemplate all non-essential changes and substitutions, such as a solid drum with continuous tooth projections, or the like, which fairly fall within the scope of the appended claims.

Having thus described my invention what I claim and desire to secure by Letters Patent is—

1. An electrical transmitter comprising a drum having ten circular groups of teeth in consecutive order from one to ten, ten contact devices coöperating with said teeth, ten circuit wires extending from said contact devices to a plurality of groups of selecting keys, each group containing ten keys connected to the respective wires in the same order from one to ten, and a plurality of controlling teeth on the drum with corresponding contact devices, and electromagnetically controlled selective means connected thereto to send impulses through the respective groups of keys during successive rotations of the drum, one digital group of impulses only for each complete rotation.

2. An electrical transmitter comprising a drum having ten circular groups of teeth in consecutive order from one to ten, ten contact devices coöperating with said teeth, ten circuit wires extending from said contact devices to a plurality of groups of selecting keys, each group containing ten keys connected to the respective wires in the same order from one to ten, a plurality of teeth arranged in helical order on a portion of the drum following the impulse teeth, with a corresponding plurality of relays controlling the circuit connections from the respective groups of keys to the transmission circuit, said relays being operated in succession, one only during each rotation of the drum, whereby a plurality of digits are transmitted by and during a corresponding plurality of complete rotations of the drum.

3. An electrical transmitter comprising a drum having ten circular groups of teeth in consecutive order from one to ten, ten contact devices coöperating with said teeth, ten circuit wires extending from said contact devices to a plurality of groups of selecting keys, each group containing ten keys connected to the respective wires in the same order from one to ten, a plurality of controlling teeth on the drum with corresponding contact devices, switching means for the several groups of keys adapted to opera-

tively connect one group only during each rotation of the drum, for transmission purposes, and electromagnetic controlling means for said switching means, adapted to 5 receive current at the end of each rotation only, through the contact devices of the controlling teeth on the drum.

4. An electrical transmitter comprising a drum having ten circular groups of teeth in 10 consecutive order from one to ten, whereby only one digit from one to ten is transmitted at each rotation of the drum, ten contact devices coöperating with said teeth, ten circuit wires extending from said contact devices to a plurality of groups of selecting 15 keys, each group containing ten keys connected to the respective wires in the same order from one to ten, a plurality of teeth arranged in helical order on a portion of 20 the drum following the impulse teeth, with a corresponding plurality of relays controlling the circuit connections from the respective groups of keys to the transmission circuit, one of said relays having its circuit 25 controlled by each of said teeth, and means for rendering only one relay at a time operative, during each complete rotation of the drum, so as to correspondingly render only 30 one group of keys at a time operative during said rotation, and so as to require a plurality of rotations to send a corresponding plurality of digits.

5. A number transmitter for multiple digit signaling system comprising a shaft, 35 a plurality of contact devices corresponding in number to the highest digit to be transmitted arranged and held in operative relation to said shaft, the highest number 40 sets of projections or teeth on said shaft arranged so that the said contact devices for each revolution of the shaft will receive impulses varying in number from the highest digit for the first contact device to the lowest digit for the last one, means for selecting impulses from one of said contact 45

devices during each of two or more rotations of the shaft, and interlocking means for the elements of the selecting means, controlled at the end of each rotation of the shaft to advance only one step at a time, and thereby 50 permit the transmission of only one digit at a time or during a single rotation.

6. An electrical transmitter comprising a drum having ten circular groups of teeth in consecutive order from one to ten, ten contact 55 devices coöperating with said teeth, ten circuit wires extending from said contact devices to a plurality of groups of selecting keys, each group containing ten keys connected to the respective wires in the same 60 order from one to ten, a number of teeth corresponding in number to the groups of keys, arranged in helical order on a portion of the drum following the impulse teeth, a pair of contacts controlled by each of these 65 teeth, a relay for each pair of contacts, said relay controlling the connection of the keys to the transmission circuit, an energizing circuit for each relay except the first controlled by the preceding relay, independent 70 means for controlling the energizing circuit of the first relay, and a locking circuit for each relay corresponding to and controlled by its corresponding contacts on the drum, whereby all the relays are set up and locked 75 for multiple digit transmission, and one at a time released, at each rotation of the drum, the first relay released connecting its own group of keys but no others to the transmission circuit, during the first rotation, the second 80 relay released similarly connecting its group of keys and no other during the second rotation, and so on.

In testimony whereof I affix my signature in presence of two witnesses.

JOSEPH LANE WRIGHT.
